UNITED STATES PATENT OFFICE.

WILLIAM CAMERON, OF CHICAGO, ILLINOIS, ASSIGNEE TO CAMERON CAN MACHINERY CO., OF CHICAGO, ILLINOIS, A CORPORATION OF ILLINOIS.

COMPOSITION-APPLYING MACHINE.

Application filed March 28, 1919. Serial No. 285,793.

To all whom it may concern:

Be it known that I, WILLIAM CAMERON, a citizen of the United States, residing at Chicago, in the county of Cook and State of Illinois, have invented certain new and useful Improvements in Composition-Applying Machines, of which the following is a specification.

This invention relates in general to composition applying machines and the embodiment disclosed herein for purposes of illustration consists of a machine for applying composition to can ends for the purpose of effecting an air tight seal between the ends and the can bodies when these ends are double seamed onto the bodies without the use of solder.

One of the primary objects of this invention is to provide a machine of this character which will be simple in construction, economical to manufacture and operate, one which will be efficient and rapid in operation and which will be capable of adjustment and adaptation to can ends of various sizes and composition of different required consistencies.

Another object of my invention is to provide a machine which will be capable of extreme rapidity in operation so that a maximum number of can ends may be compositioned in a given time, and with this end in view my machine is constructed to operate upon two can ends simultaneously.

A further object is to prevent injury to the machine in the event of a mis-feed which might result from the feeding of an imperfect end which would cause the feeding mechanism to jam.

Other objects and many of the inherent advantages of this invention will be readily understood and appreciated by reference to the following description when considered in connection with the accompanying drawings illustrating one preferred embodiment of the invention.

Referring to the drawings,—

Fig. 1 is a plan view of the machine embodying my invention;

Fig. 2 is an elevation looking at the near side of the machine shown in Fig. 1;

Fig. 3 is an elevation looking toward the right at the machine shown in Fig. 1;

Fig. 4 is a sectional view taken substantially on the line 4—4 of Fig. 1;

Fig. 5 is a sectional view on the line 5—5 of Fig. 1;

Fig. 6 is a transverse sectional view through one of the can end magazines;

Fig. 7 is a longitudinal sectional view through one of the magazines; and

Fig. 8 is a perspective view of one of the can end separating and feeding devices.

By reference to the drawings it will be observed that the machine comprises primarily a base or pedestal portion 9, an upright portion 11, and a top portion 12, all preferably of cast construction carrying the operating mechanism of the machine. The upright portion 11 is divided by a central vertically disposed partition 13 into two compartments or tanks 14 and 15, respectively, each adapted to contain a quantity of the liquid composition which is to be applied to the can ends. Each tank is equipped with a filling spout 16 normally sealed by a plug 17 and each is also provided near the bottom with a hand hole which is covered and sealed by a plate 18, this hand hole serving as a medium of access to the interior of the tank for cleaning purposes.

The composition in each tank is delivered therefrom under pressure and the pressure in each tank is maintained by an air-compressor 19 of any preferred construction. The compressors herein shown are of the reciprocating type driven from eccentrics 21 mounted upon the main drive shaft 22 of the machine which is driven from any suitable source of power through a drive pulley 23. This pulley may be clutched to or unclutched from the drive shaft by means of the clutch 24, of any preferred type, which may be actuated by a lever 25 at one side of the machine and for purposes of convenience and accessibility a second clutch lever 26 is provided at the opposite side of the machine and connected with the lever 25 by a link or rod 27. Each tank is also equipped with a gage 28 through which the height of the liquid level in the tank may be observed and a pressure gage 29 is also provided for each tank in order that the pressure therein may be observed. For the purpose of preventing an accumulation of excess pressure and in order that the pressure in the tank may always be at or substantially near the required maximum, each tank is equipped with a relief valve 31 which may be set by means

75

of an adjusting screw 32 to blow off at any predetermined maximum pressure.

The composition is delivered under the requisite pressure from each tank near the bottom thereof through a pipe line consisting of a vertical portion 33, a horizontal portion 34 and a vertical portion 35 to a chamber 36 (Fig. 5) from whence it is discharged through the applying nozzle, which will be 10 later explained. The upright portion 33 of the line terminates at its upper end in a coupling member 37 which is supported upon a bracket 38 projecting laterally from the top 12. The adjacent end of the horizontal portion 34 of the line is equipped with a companion coupling member 39 and between these two members I interpose a screen 41 which cleans the composition and prevents the delivery of sediment or the like to the 15 nozzle which might clog the same so as to shut off or reduce the flow of the requisite amount of composition therefrom at each delivery operation. The coupling member 39 is forced toward the member 37 to clamp the 20 meshed screen between these members by means of a clamping screw 42 threaded through a tapped boss 43 on the side of the top member 12. The pipe line is also preferably equipped with a shut-off cock 44 by 25 which the flow of composition may be shut off or regulated when desired.

Each tank is provided with a stirrer or agitator 45 carried by a vertical shaft 46 which is rotated by means of a large gear 47 at its upper end, these gears being driven from a large driving gear 48 mounted upon the upper end of a vertical shaft 49 which is equipped at its lower end with a bevel gear 51 which meshes with and is driven by 30 a bevel pinion 52 on the drive shaft 22. This drive shaft is provided at its left hand end, viewing Figs. 1 and 2, with a hand wheel 53 by means of which the machine may be turned over by hand when occasion requires. 35 Each of the gears 47 is adapted to drive a reciprocating can end feeding device which consists primarily of a slide member 54 mounted to reciprocate in guideways formed on the upper side of the top member 12, suitable under-cut plates 55, 56, and 57 being bolted to the upper side of the top member and undercut so as to overlie the edges of the slide members 54 to retain these members in position during their reciprocating movements. Each slide member 54 is pivotally connected by means of a depending stud 58 with a link or pitman which is connected at 50 its other end with its gear 47.

Referring to the gear and slide member 60 shown at the right in Fig. 1, it will be observed that the gear is provided with an up-standing pivotal stud 59 and connection is established between the stud 59 and the stud 58 through a pitman 61 which comprises two 65 pivotally connected jaws, the movable one

62 of which is urged toward the other jaw by a spring 63 interposed between this jaw and the head of a bolt 64 passing through the movable jaw and threaded into the stationary jaw. Each of the jaws is equipped 70 near its end with a semi-circular recess or socket so that the stud 59 is embraced by the two jaws, establishing thereby a driving connection between the gear and its slide member 54. Should excessive strain be imposed 75 upon the slide member by a jam resulting from an imperfectly formed can end or from other causes, the spring 63 will yield under the excessive strain permitting the jaws to separate and release from the stud 59, thereby breaking the driving connection and permitting the slide member to stop so that no injury to the machine will result. This connection may also be disconnected at will 80 in case it should be desirable to operate one 85 of the slide members only, and when this connection is released the slide member at the right of the machine will remain stationary while the other slide member will continue to operate. 90

A releasable driving connection between the other gear 47 and its slide member 54 is also provided but this connection is adapted to automatically re-establish or reconnect itself without the necessity of manual connection. The driving pitman 65, in this instance, is pivoted to the stud 58 at one end and to an upwardly projecting stud 66 at its other end, the pitman being of rigid construction. The stud 66 is mounted on a disk 100 67 mounted concentrically with the gear 47 but structurally independent thereof.

A spring-pressed plunger 68 mounted in a radial socket 69 in the disk 67 is normally urged outwardly into engagement with a 105 socket 71 formed on the inner periphery of the gear wheel 47. The outer end of the pin 68 is rounded, as shown in Fig. 1, and when excessive strain is imposed on the slide member the pin 68 will be forced inwardly 110 against the tension of its spring so as to release from its socket 71, thereby permitting the disk 67 to stand still while the gear 47 revolves. Each time the socket 71 is brought into alignment with the plunger 68 the plunger will be projected into this socket and after the obstruction to the slide member 54 has been removed the driving connection will be automatically re-established, but so long as opposition to movement of the slide member is excessive the plunger will not permanently engage with its socket and the disk 67 will remain motionless while the gear continues to revolve. 115

The slide members 54 are adapted to convey can ends from the magazines to composition applying stations and from the stations to a delivery point at the rear of the machine. Above each slide member there is mounted a magazine adapted to contain can 120 125 130

ends in stacked relation. These magazines consist each of a plate 72 mounted upon the top of the machine and carrying vertically disposed posts 73 between which the can ends 74 (Figs. 6 and 7) are stacked. Each slide member is bifurcated for some distance from its rear end, providing a space between the bifurcations of greater width than the diameter of the can ends to be fed, and at 5 the forward ends of these bifurcations a shoulder 75 is formed where the bifurcations merge into the slide member proper, which, when the slide member is in its extreme forward position, as shown at the left in Fig. 1, 10 will be disposed forwardly of the magazine so that a can end in the magazine will drop down back of the shoulder. The extremities of the bifurcated portion of the slide members are turned inwardly, as indicated at 76, 15 so that the distance between them is less than the diameter of the can ends to be operated upon. When a can end in the magazine has been positioned in front of the shoulder 75, as shown at the left of Fig. 1, 20 upon rearward movement of the slide member to the position of the one shown at the right in Fig. 1, this lowermost can end will be carried rearwardly a distance equal to the length of stroke of the slide member. When 25 this distance has been traversed the can end has been positioned at the composition applying station and directly over a chuck head 77 mounted upon a rotatable and vertically reciprocable spindle 78 which is guided 30 in its movements in a bearing 79 attached to the body of the machine, as shown in Fig. 4. This chuck head is normally maintained in its lower position, as shown in Figs. 4 and 5, 35 by an expansion spring 81 surrounding the spindle and disposed between the lower end of the bearing 79, and a washer 82 secured to the lower end of the spindle. These spindles are continuously revolved at a relatively high speed by pinions 83 fixed on the 40 spindles and meshing with the driving gear 48, 45 and it will be observed that the pinions 83 are of considerable length so that the required vertical movements of the spindles may be effected without disturbing the driving 50 relation between the gear 48 and the pinions 83.

A can end having been advanced from the magazine by the shoulder 75 on the slide member to a position directly over the 55 chuck head 77, as just explained, the chuck head is now elevated carrying the can end upwardly with it and while in elevated position the slide member is retracted. The inwardly projecting fingers 76 on the slide 60 member are spaced apart far enough to clear the spindle 78 when in raised position so that upon the retracting movement of the slide member these fingers pass beneath the elevated chuck head. During the time that the 65 shoulder 75 is moving from the magazine to

the composition applying station and back again, the can ends in the magazine are supported upon the slide member 54. Each slide member is equipped adjacent the shoulder 75 with two plates 84, one at each side, as 70 shown in Figs. 4 to 8 inclusive, and these plates are equipped at their forward ends with beveled surfaces 85 adapted to act as separators for the can ends in the magazine. As the slide members are retracted these 75 beveled surfaces enter between the lowermost can end in the magazine and the next superposed end, and as the member continues its retractive movement the entire stack of ends, with the exception of the lowermost one, is lifted by the inclined surfaces 85 in the manner shown in Fig. 7, and supported during the remainder of the retractive stroke upon the plates 84. When the shoulder 75 clears the magazine on the re- 80 tractive stroke the lowermost end will drop into horizontal alignment with the shoulder and upon reverse movement of the slide member this end will be carried to the composition applying station, and after the 90 plates 84 move out from beneath the stacked ends in the magazine these ends will be supported upon the slide member 54.

While the slide member was in retracted position the chuck head 77 was lowered, 95 thereby bringing the can end on the head into the path of the slide fingers 76, as shown at the left in Fig. 1, and upon feeding movement of the slide member this end, which has in the meantime been operated upon, will 100 be advanced from the applying station to the rear end of the machine where it is delivered from the machine, as shown at the right in Fig. 1. It will be observed that the two slide members are so connected to their 105 respective driving gears 47 that they are operated in alternation with the result that the ends are fed alternately from the two magazines and are alternately operated upon at the applying station. 110

The mechanism for raising and lowering the chuck spindles 78 is best shown in Figs. 2 and 4, from which it will be observed that upon the vertical shaft 49 there is mounted a cam 86. At each side of this cam there 115 is pivotally mounted at 87 upon the body of the machine an arm 88 carrying at its inner end a cam follower 89 which rides upon the cam 86. The outer end of each arm 88 is equipped with a bearing roller 91 120 disposed directly beneath the head of a screw 92 threaded into the lower end of the spindle 78. As the arm 88 is raised by the cam, the spindle 78 is moved upwardly into the position shown at the right in Fig. 2, 125 and when the lower portion of the cam travels beneath the roller 89 the spindle is lowered by the expansion spring 81. Thus it will be seen that the spindles and chuck heads are raised and lowered in alternation 130

and in proper timed relation with the reciprocatory movements of their respective slide members 54. When the chuck heads are completely lowered they are disposed 5 slightly below the plane of the advancing can ends, as shown in Fig. 5, so that an end may be positioned above the revolving head by its slide member without coming in contact with the head. When an end has been 10 thus positioned the revolving head is elevated in the manner just described, carrying upwardly with it the positioned can end which is thereupon rapidly rotated with the head upon which it is supported. It is while 15 the end is elevated and is being revolved that the composition is applied thereto in the groove near the periphery of the end and the application of the composition to the end is effected by mechanism best illustrated 20 in Fig. 5, which will now be described.

The composition is continuously delivered from the tank to the chamber 36, as has been previously explained. In the block in which this chamber is formed there is ad- 25 justably mounted a tube 93 provided with a port 94 registering with the chamber 36 and permitting considerable longitudinal adjustment of the tube without disturbing the registration. The outer end of the tube 30 is closed by a plug 95 which may be removed to enable the tube to be cleaned. The tube is clamped in the block by clamping bolts 96 (Fig. 3) and by loosening these bolts longitudinal adjustment of the tube may be 35 accomplished. The inner end of the tube carries a vertically disposed nozzle designated generally by reference 97, the nozzle proper 98 having a small delivery orifice 99 at its lower end and being removably 40 threaded into the body of the nozzle so that it can be removed for cleaning purposes. Within the nozzle body there is disposed a shut-off valve 101 adapted to seat in the tapered nozzle tip 98 to shut off the flow 45 of composition from the nozzle and this valve is normally held in seated position by an expansion spring 102 surrounding the valve stem 103 and bearing at its lower end upon a collar 104 fixed to the valve stem 50 and at its upper end against the closure 105 which is encased in a suitable packing gland 106. The upper end of the valve stem is provided with a laterally extending slotted arm 107 which is connected by clamping 55 nuts 108 to a vertically reciprocable rod 109 mounted in a bearing 111, the lower end of this rod having a rounded head 112 disposed in axial alignment with its chuck head 77.

60 The parts just described normally assume the position shown in Fig. 5, in which the nozzle out-let is closed and no discharge of composition can take place. When the revolving chuck head, however, is elevated, 65 in the manner previously described, the

can end is carried upwardly against the head 112 of the rod 109, thereby moving this rod upwardly which, through the connected bar or arm 107, carries the valve stem 103 upwardly so as to withdraw the valve 101 from its seat against the force of its spring 102, thereby permitting the composition to be delivered under pressure from the nozzle directly into the peripheral groove of the rapidly revolving can end which is now in close proximity to the discharge orifice of the nozzle. The valve remains open for a pre-determined period and the application of the composition to the can end continues until the chuck head is lowered, whereupon the valve is closed by the spring 102 and the flow of composition is shut off. Since the operation of the machine is very rapid, it will be manifest that the valve is maintained in open position just long enough to deliver 85 the requisite quantity of composition to the can end where it is applied over the desired surface.

It will be obvious that the adjustable mounting of the nozzle supporting tube 93 and the slotted connection between the bar 107 and the rod 109 permits the nozzle to be adjusted with a fine degree of nicety so that the composition is delivered at exactly the right point to the can end and that this adjustment also enables the nozzle to be adjusted inwardly and outwardly to accommodate the same to can ends of different diameters. After the desired adjustment has been secured the bolts 96 and the nuts 108 100 are, of course, tightened up again.

The operation of the machine is briefly as follows: The composition, under pressure, is maintained at all times in the nozzle; the can ends are stacked in the magazines and upon each rearward movement of a feeding slide, one can end is moved by the shoulder 75 from the magazine to the applying station and the end at the station which has received its composition is delivered from the machine simultaneously by the fingers 76. Upon return stroke of the feeding device the fingers 76 travel beneath the then elevated chuck head and the separating plates 84 separate the lowermost can end in the magazine from the remainder of the stack and this end drops into alignment with the shoulder 75, to be thereby advanced on the next advancing movement of the slide member. The can end at the applying station is elevated and rapidly revolved by the chuck head and its upward movement into proximity to the applying nozzle causes the nozzle valve to be opened so as to permit the delivery of the requisite amount of composition by the nozzle to the end.

It is believed that my invention and the construction and mode of operation of the embodiment selected for purposes of illustration will be fully understood from the 130

foregoing without further description, but it should be manifest that the invention is not limited to the details shown and described but is capable of considerable modification 5 and variation as to its structural embodiment without departing from the essence of the invention as defined in the following claims.

I claim:

10 1. In a composition applying machine, the combination of a plurality of magazines adapted to contain can ends, a plurality of composition applying stations each including a reciprocatory chuck head, feeding mechanisms for advancing can ends from said magazines to said stations, means for operating said mechanisms and chuck heads in alternate timed relation, and means for automatically applying composition to a can end 20 at each of said stations in alternation.

2. In a composition applying machine, the combination of a plurality of magazines adapted to contain can ends, a plurality of composition applying stations, mechanisms 25 for advancing can ends from said magazines to said stations, means for actuating said mechanisms in pre-determined timed relation with respect to each other, means whereby one of said can end advancing means may 30 be thrown out of operation without affecting the other, and means whereby said other can end advancing means will be automatically stopped when excessive strain is imposed thereon.

35 3. In a composition applying machine, the combination of a plurality of tanks adapted to contain composition, means for maintaining the composition in each tank under a pre-determined pressure, a plurality of magazines adapted to contain can ends, a plurality 40 of composition applying stations, means for automatically feeding can ends in alternation from said magazines to said stations, means for revolving the can ends at said 45 stations, and means for alternately applying composition from each tank to its respective revolving can end.

4. In a composition applying machine, the combination of a frame, a tank disposed in 50 the lower portion of said frame and adapted to contain composition, a pump mounted on said frame for maintaining the composition in said tank under pressure, a can end magazine mounted on said frame above the tank, 55 a composition applying station also disposed above said tank, means for feeding can ends in succession from said magazine to said station, a delivery nozzle at said station, means for engaging the center of a can cap at said station, and a valve connected to 60 and directly operated by said cap engaging means for controlling the flow of composition from said nozzle.

5. In a composition applying machine, the 65 combination of a tank adapted to contain

composition under pressure, a vertically reciprocable chuck head, means for feeding can ends thereto, a delivery nozzle adapted to deliver composition from said tank to a can end on said chuck head, a clamping 70 rod disposed concentrically above said head and adapted to retain a can end thereon, a valve in said nozzle, and means operated by said rod for opening said valve to permit the delivery of composition to said can end. 75

6. In a composition applying machine, the combination of a chuck head, means for continuously rotating the same, means for intermittently reciprocating said head longitudinally, a clamping rod disposed centrally 80 above said head, means for automatically feeding can ends into position between said head and said rod, a composition delivery nozzle disposed in proximity to said rod, means for supplying composition under pressure to said nozzle, a valve connected to said rod to be opened by upward movement of said rod, and means for depressing said rod and closing said valve.

7. In a composition applying machine, the combination of a vertically reciprocable chuck head, a clamping rod disposed above 90 said head, means for feeding a can end into position between said head and said rod, a composition delivery nozzle disposed in 95 proximity to said rod, a valve in said nozzle, a spring normally closing said valve, and a connection between said valve and said rod whereby said valve is opened through the instrumentality of said rod and connection upon upward movement of said chuck head.

8. In a composition applying machine, the combination of a vertically reciprocable chuck head, a vertically movable rod disposed above and in alignment with said head, a composition delivery nozzle, means for adjustably supporting said nozzle in proximity to said head, a valve in said nozzle, and an adjustable connection between 105 said valve and said rod through which said valve is actuated upon movement of said rod by said chuck head.

9. In a composition applying machine, the combination of a tank adapted to contain composition, a delivery nozzle provided with a laterally extending tubular support through which composition is delivered to said nozzle, a hollow bearing member in which said support is adjustably mounted 115 to permit adjustment of said nozzle, and a connection between said bearing and said tank through which composition is supplied from the tank to the bearing, said nozzle support being provided with a port communicating with the interior of said bearing through which composition is supplied to said nozzle in any adjusted position of said nozzle.

10. In a composition applying machine, 130

- the combination of a hollow bearing member, a tubular nozzle supporting member adjustably mounted in said bearing member, a nozzle carried by said supporting member, a passage in said bearing member communicating with the bore of said supporting member through a port in said supporting member, and means for supplying composition under pressure to said passage.
10. 11. In a composition applying machine, the combination of a hollow bearing member, a nozzle supporting member adjustably mounted therein, a nozzle carried by said supporting member, said supporting member being provided with a longitudinal bore communicating at one end with said nozzle and having a lateral port communicating with a passage in said bearing member in any adjusted position of the nozzle, and a removable plug closing the outer end of said bore.
12. In a composition applying machine, the combination of a frame, a vertically disposed chuck head mounted on said frame, means for continuously rotating said head, a spring tending to normally hold said head in lowered position, a pivotally mounted member disposed in axial alignment with said head, means for intermittently actuating said member to elevate said head against the force of said spring, and adjustable means whereby the extent of elevating movement of said head may be regulated.
13. In a composition applying machine, the combination of a frame, a pair of vertically disposed bearings, a spindle rotatably mounted in each bearing, a chuck head carried by each spindle, means for continuously rotating said heads, a pivotally mounted member positioned beneath each of said spindles, a cam for actuating said members in predetermined timed relation, and means whereby the reciprocatory movements of said spindles may be regulated.
14. In a composition applying machine, the combination of a frame, a plurality of longitudinally movable spindles mounted thereon, means for continuously rotating said spindles, a pivotally mounted member disposed beneath each of said spindles, and a cam common to both of said members for actuating the same whereby said spindles are reciprocated in alternation.
15. In a composition applying machine, the combination of a vertically reciprocable spindle, a chuck head carried thereby, a magazine for can ends, a reciprocatory can end feeding device comprising a shoulder for feeding the ends from the magazine to said spindle, and a bifurcated portion having inturned fingers adapted to push a cap off from said head upon feeding movement of said device and adapted to pass upon opposite sides of said spindle upon return movement of said device.
16. In a composition applying machine, the combination of a vertically reciprocable spindle, a chuck head carried thereby, a magazine for can ends, and a reciprocatory feeding device comprising a shoulder for feeding can ends from the magazine to said chuck head and a pair of opposed fingers spaced apart and spaced from said shoulder, the distance between said fingers being less than the diameter of the chuck head, but greater than the diameter of the spindle to remove a can end from said chuck head when the same is in lowered position and to pass beneath said chuck head and upon opposite sides of said spindle when the chuck head is in elevated position.
17. In a composition applying machine, the combination of a frame, a plurality of rotatable and longitudinally reciprocable spindles, a chuck head carried by each spindle, means for rotating said spindles, a cam, and means pivotally mounted on said frame interposed between said cam and each of said spindles whereby said spindles are reciprocated in alternation from said cam.
18. In a composition applying machine, the combination of a pair of vertically reciprocable spindles, chuck heads carried thereby, can end magazines, means for feeding can ends from said magazines to the respective chuck heads, said means each comprising shoulders for feeding can ends from the magazines and fingers spaced from said shoulders and adapted to deliver can ends from the chuck head, said fingers being spaced apart to straddle the spindle upon return movement of the feeding means, and mechanism for actuating said feeding means in predetermined timed relation.

WILLIAM CAMERON.
